EXTENSION LOUD-SPEAKER

Owsiej Plawczyk, London, England

Application January 21, 1949, Serial No. 382
In Great Britain September 22, 1948

Term of patent 14 years

(Cl. D26—5)

To all whom it may concern:

Be it known that I, Owsiej Plawczyk, a subject of the King of Great Britain, residing at 78 Brondesbury Road, London, N. W. 6, England, have invented a new, original, and ornamental Design for an Extension Loud-Speaker, of which the following is a specification, reference being had to the accompanying drawing, forming part thereof.

Fig. 1 is a perspective front elevational view of an extension loud-speaker, showing my new design.

Fig. 2 is a perspective rear elevational view thereof.

Fig. 3 is a perspective view to show the base, with the article turned on its face.

Fig. 4 is a vertical cross-sectional view of the front face of the loud-speaker, taken on line 4—4 of Fig. 1.

Fig. 5 is a horizontal cross-sectional view of the front face of the loud-speaker, taken on line 5—5 of Fig. 1.

I claim:

The ornamental design for an extension loud-speaker, as shown and described.

OWSIEJ PLAWCZYK.
